WILLIAM E. FOSTER, OF CLEVELAND HEIGHTS, OHIO

SOUND-ABSORBING STRUCTURE

Application filed April 17, 1929. Serial No. 355,909.

This invention relates to a structure for producing an improvement in the acoustics of auditoriums.

Heretofore, it has been regular practice to apply sound-absorbing material to the walls and ceiling of an auditorium for the purpose of preventing echo. It is also a well-known fact that the seat cushions of a church auditorium, for instance, may be depended upon as a sound-absorbing means, although the sound-absorbing effect of the cushions is automatically eliminated when the auditorium becomes filled. Moreover, cushions are omitted in most cases today, due to excessive cost, and can not well be later added, as explained below.

In an actual instance of a particular church auditorium known to the present applicant, the period of vibration when the auditorium is empty is 3.5. That is to say, the vibration of sound will continue for 3.5 seconds. Then when the same auditorium is completely filled, the period of vibration is reduced to 1.8. In this particular instance, the ideal condition with respect to the period of vibration is 2. Thus, it is quite apparent that when the auditorium is empty, there would be a pronounced vibration of sound resulting in the objectionable echo, and the ideal condition is realized only when the auditorium is almost completely filled. In other words, the period of vibration varies according to the number of people in the auditorium and thus there results a variable factor beyond control, so far as the ideal condition with respect to vibration is concerned.

With the present existing condition as above briefly referred to, there has been experienced a need in some instances for a greater degree of sound-absorbing capacity, since in such cases the walls and ceiling of the auditorium are not sufficient for this purpose. Furthermore, in all instances, there has been felt also a need of being able to regulate or control the period of vibration for all conditions, that is, regardless of whether the auditorium is empty, partially filled, or completely filled. It is, therefore, the object of the present invention to devise a means for accomplishing this end.

The problem, as above indicated, has been practically solved, as a result of the discovery that the application of a sound-absorbing means to the under-side of the pew or other form of seat in the church or other auditorium may be depended upon to accomplish the purpose as above outlined. In this way, there is afforded the increased surface area for the application of sound-absorbing material; and such material when applied in this manner, will be in the path of the sound which is reflected from the floor of the auditorium. Furthermore, the sound-absorbing effect of such material, when applied in this manner, will be realized at all times to the proper degree, that is, regardless of whether the auditorium is filled or empty. In this way, the period of vibration of the auditorium when empty may be made to approximate the ideal condition without interfering with the same ideal condition when the auditorium is completely filled. The legs of the occupants of the seats, to the under-side of which the sound-absorbing material is applied, will somewhat reduce the sound-absorbing effect of such material when the auditorium is filled, yet this reduction is compensated for by the sound-absorbing effect of the occupants, and there is thus obtained the proper degree of sound absorption at all times regardless of the number of people in the auditorium. Also, the sound that is produced by the shuffling of the feet of those occupying the seats will be absorbed in a very effective manner by means of the present invention. The effect of the sound-absorbing material applied to the under-side of the seats is thus automatically regulated according to the degree to which the auditorium is filled. In fact, practical experience has already demonstrated that the sound-absorbing material when applied to the under-side of the seats, as herein disclosed, may be depended upon as an automatically compensating variable for all conditions of the auditorium, that is, regardless of the degree to which the auditorium may be filled. There may be employed any desired sound-absorbing material and it may be applied to the extent required

by the particular set of conditions in a given case.

Fig. 1 is a perspective view of a church pew embodying my present invention; Fig. 2 is a 5 sectional view taken on line 2—2 of Fig. 1; and Fig. 3 is an inverted plan view of Fig. 1.

Referring to the accompanying drawings, the sound-absorbing material 1 is indicated as applied to the under-side of the seat portion 2 10 of the pew, the lower part of which is so constructed and arranged that the under-side thereof will be exposed to the sound vibrations. In the present case, the pew is provided with the legs 3, while the remaining 15 portion of the pew is left open at the under-side thereof. The sound-absorbing material 1 may be of any suitable nature or form and may be applied to the under-side of the pew in various manners. In the present case, a 20 molding 4 engages the edge portion of the material 1 as a means of attaching the same to the under-side of the pew.

It is to be understood that the sound-absorbing material 1 may be applied by the 25 manufacturer to the under-side of the pew as an insert and may in such case be considered as forming a part of the pew in its original construction. Various other modifications may be adopted without departing from the 30 spirit of the present invention.

Another advantage consists in the fact that the sound-absorbing material may be applied to the under-side of a pew which has already been installed in a church auditorium. But 35 cushions can not be added to pews which were not originally designed therefor, for the reason that the curvature of the pews must be designed originally according to whether or not cushions are to be used. Then the later 40 addition of cushions to pews not originally so designed would destroy the proper effective curvature of the pews. Furthermore, the application of the present invention to a church pew or the like, either during the process of 45 construction thereof or after its installation, is comparatively inexpensive and may be applied in a convenient manner without involving the use of scaffolding or the like which is required in the application of sound-absorbing material to the walls and ceiling 50 of an auditorium. Also, the sound-absorbing material, when applied in the manner herein described, is practically out of view and hence is free of any objection because of 55 the appearance of the particular material selected; and at the same time, the sound-absorbing material is arranged in such position as to be protected against damage. The sound-absorbing material may be applied to 60 only as many pews as may be necessary in a particular case, and yet such an arrangement is not unsightly since it is not noticeable to the public.

As above stated, the principal advantage 65 resulting from the present invention resides

in the fact that the period of vibration is now placed more nearly under perfect control regardless of whether the auditorium is empty or partially or completely filled.

What I claim is:

1. The combination of a seat having its under-side exposed to sound vibrations, and sound-absorbing means applied to the under-side thereof, said means having a greater sound-absorbing capacity than the material 75 of the seat itself.

2. A device of the class described, comprising a seat having its under-side exposed to sound vibrations, and being provided upon its under-side with sound-absorbing material 80 capable of greater sound absorption than the material of the seat itself.

3. The combination of an inflexible seat portion having its under-side exposed to sound vibrations, and separate sound-absorbing material secured directly to the under-side thereof, said material having a greater sound-absorbing capacity than the material 85 of the seat portion itself.

4. A device of the class described, comprising an inflexible seat portion having its under-side exposed to sound vibrations, and being provided upon its under-side with sound-absorbing means capable of a relatively high degree of sound absorption. 90

5. A device of the class described comprising a seat portion formed of inflexible material and being provided therebeneath with sound-absorbing means, said means being exposed directly to the sound waves reflected from the floor and having a greater sound-absorbing capacity than the material of the seat portion itself. 100

In testimony whereof, I hereby affix my signature.

WILLIAM E. FOSTER.
